UNITED STATES PATENT OFFICE

149,137

DESIGN FOR A SEWING MACHINE HEAD

Walter F. Nessen, Prospect Heights, Ill., assignor
to Free Sewing Machine Co., Rockford, Ill., a
corporation of Illinois

Application August 2, 1946, Serial No. 132,251

Term of patent 14 years

(Cl. D70—1)

To all whom it may concern:

Be it known that I, Walter F. Nessen, a citizen of the United States, residing at Prospect Heights, in the county of Cook and State of Illinois, have invented a new, original, and ornamental Design for a Sewing Machine Head, of which the following is a specification, reference being had to the accompanying drawing, forming part thereof.

In the drawing:

Fig. 1 is a front perspective view of a sewing machine head embodying the design of my invention;

Fig. 2 is a rear perspective view, and

Fig. 3 is a top view.

The essential features of my design reside in the portion shown in solid lines.

I claim:

The ornamental design for a sewing machine head, substantially as shown and described.

WALTER F. NESSEN.
